Primary Examiner — Kevin K Rudzinski*Assistant Examiner* — Richard E Yenchesky(74) *Attorney, Agent, or Firm* — Birch, Stewart, Kolasch & Birch, LLP(57) **CLAIM**

We claim the ornamental design for a hanger for clothing care machine, as shown and described.

DESCRIPTION

FIG. 1 is a front perspective view of a hanger for clothing care machine showing the new design:

FIG. 2 is a bottom perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a perspective view showing a state of use thereof.

The broken lines showing portions of a Hanger for clothing care machine and portions of a clothing care machine in FIG. 9 form no part of the claimed design.
